Specification for Design.

Patented May 10, 1921.

Application filed November 13, 1920. Serial No. 423,991. Term of patent 14 years.

To all whom it may concern:

Be it known that I, EMANUEL JACOB, a citizen of the United States, residing in the city, county, and State of New York, have invented a new, original, and ornamental Design for a Ticket for Net Goods or Veilings, of which the following is a specification, reference being had to the accompanying drawing, forming part thereof, in which—

Figure 1 is a perspective view of a ticket for net goods or veilings, showing my new design;

Fig. 2 is a side elevation of the same;

Fig. 3 is a sectional view on the line 3—3 of Fig. 1, looking in the direction of the arrows, and

Fig. 4 is a sectional view on the line 4—4 of Fig. 1, looking in the direction of the arrows.

I claim:—

The ornamental design for a ticket for net goods or veilings, as shown.

EMANUEL JACOB.
